US0D1086161S

(12) **United States Design Patent** (10) **Patent No.:** **US D1,086,161 S**
(45) **Date of Patent:** **** Jul. 29, 2025**

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Kuonyoung Seo**, Suwon-si (KR); **Miyeon Park**, Suwon-si (KR)

(73) Assignee: **Samsung Electronics Co., Ltd.**, Suwon-si (KR)

(**) Term: **15 Years**

(21) Appl. No.: **29/894,941**

(22) Filed: **Jun. 15, 2023**

Related U.S. Application Data

(63) Continuation of application No. 29/785,759, filed on May 27, 2021, now Pat. No. Des. 996,449.

(30) **Foreign Application Priority Data**

Dec. 24, 2020 (KR) 30-2020-0064999
Dec. 24, 2020 (KR) 30-2020-0065003

CLAIM

The ornamental design for a display screen or portion thereof with graphical user interface, as shown and described.

DESCRIPTION

The sole FIGURE is a front view of a display screen or portion thereof with graphical user interface showing our new design.

The outermost broken lines in the FIGURE show a display screen or portion thereof and form no part of the claimed design.

The remaining broken lines in the FIGURE depict portions of the graphical user interface which form no part of the claimed design.

1 Claim, 1 Drawing Sheet
